UNITED STATES PATENT OFFICE.

JOHN O. CARREY, OF ST. LOUIS, MISSOURI, ASSIGNOR TO C & C ENGINEERING CO., INC.,
OF ST. LOUIS, MISSOURI, A CORPORATION OF MISSOURI.

COMPRESSOR.

Application filed February 20, 1926. Serial No. 89,634.

This invention relates to new and useful improvements in compressors and has for its objects the provision of a compressor wherein the valves are dispensed with and the intake and discharge of the fluid from the compressor chamber or cylinder is controlled by the movement of said cylinder which is mounted for oscillatory movement and has a closed ported head which 5 cooperates with a stationary plate provided with intake and outlet ports whereby the oscillatory movement of said cylinder positions the ported head thereof in register with the intake or the outlet port of said plate in correlation with the movement of the piston.

10 Further objects of the invention are to provide actuating connections for the piston of said cylinder to cause oscillatory movement of the latter and bring the port thereof in register with the proper port of the plate automatically and in time relation with the movement of said piston.

15 Additional objects of the invention are to generally improve upon and simplify the construction of the compressor of the class described and permit the coupling of said compressor directly to the prime mover, such as an electric motor, thereby eliminating 20 expensive and noisy operating connections and condensing the compressor structure so that it occupies a minimum amount of space and is of durable construction.

25 Further objects of the invention are to provide suitable means mounted in the casting of the compressor for oscillatory movement and adapted removably to receive the cylinders and support them in proper operative positions.

30 Still further objects of the invention are to provide means automatically operable in correlation with the compressor for bypassing the discharge port of the cylinder when the compressor is stationary in order to prevent the compressing of the fluid during 35 the stationary operation of the compressor, thereby relieving the prime mover utilized to operate the compressor of unnecessary load during the starting operation thereof, said means being automatically operable when the compressing mechanism attains its proper speed to bring the discharge port 40 of the cylinder or cylinders in communication with the port of the high pressure chamber.

With these and other objects in view, my invention consists in certain novel features of construction and arrangement of parts, hereinafter more fully described and claimed, and illustrated in the accompanying drawings, in which—

Figure 1 is a vertical cross section taken longitudinally through my improved compressor.

Figure 2 is a transverse cross section taken vertically on line 2—2 of Figure 1.

Figure 3 is a detail view of the upper portion of the compressor showing the cylinder in moved position in register with the discharge port of the compressor.

Figure 4 is a similar view showing the cylinder in reverse position in register with the intake port of the compressor.

Figure 5 is a bottom plan view of the ported plate adapted to cooperate with the head of the cylinder.

Figure 6 is a top plan view of the head of the cylinder.

Figure 7 is a longitudinal cross section through the coupling and seal used in connection with my compressor.

Figure 8 is a vertical cross section taken on line 8—8 of Figure 7.

Figure 9 is a vertical cross section taken on line 9—9 of Figure 7.

Figure 10 is an enlarged detail view showing the packing interposed between the adjacent surfaces of the bearing plate and the wall of the high compression chamber.

Figure 11 is a detail view showing in section a modified form of the cylinder.

Figure 12 is a fragmental sectional view through my improved compressor showing the automatically operable means for unloading or by-passing the compressor.

Figure 13 is a similar view but showing the actuating mechanism of the by-passing means in moved or operative position.

Figure 14 is a transverse section taken on line 14—14 of Figure 13.

Figure 15 is a detail view showing the actuating arm of the sleeve in retracted position.

Figure 16 is a similar view but showing said arm in moved position, which position it assumes when the compressor is running at full speed.

Figure 17 is a transverse section through the cylinder chamber showing the cylinder in communication with the outlet port of

the high pressure chamber and the sleeve in operative position, which position it assumes when the compressor is operating at full speed.

5 Figure 18 is a similar view but showing the sleeve in moved or inoperative position, which position it occupies when the compressor is stationary.

10 Figure 19 is a similar view showing a modified form of construction.

Referring by numerals to the accompanying drawings, 10 indicates a casing of the compressor which is preferably cylindrical in shape and is supported by a support or 15 saddle 11 which is secured thereto by suitable fastening means 12. Casing 10 is provided with an extension 10^a which is also cylindrical in shape but of smaller diameter, and the upper end of said extension is provided with a high pressure chamber 14 which is closed by a plate 15. The ends of casing 10 are closed by end plates 16 which are provided with extensions 16^a and 16^b for closing the ends of extension 10^a and chamber 14, respectively.

30 End plates 16 are provided with inwardly extending circular flanges 17 in which are arranged bearings 18 for receiving shaft 19. One end of said shaft projects through one of the end plates and is adapted to be connected in any suitable manner to a prime mover such as an electric motor. A pair of oppositely disposed eccentrics 20 is arranged on shaft 19 and operating on 35 said eccentrics are sleeves or collars 21 which are formed integral with or secured to the lower ends of pistons 22. Each piston 22 is disposed above shaft 19 and operates in a cylinder 24 which is disposed in chamber 25 formed in extension 10^a and is supported 40 therein by a sleeve 26 which is slipped over said cylinder and bears at one end against a circular shoulder 24^a which is formed integral with said cylinder, while the opposite 45 end is engaged by a threaded collar 27 screw-seated on the threaded portion of cylinder 24 so that by tightening collar 27, sleeve 26 is securely clamped in position on the piston. Each sleeve 26 is provided with 50 outwardly projecting trunnions 28 which are journaled in bearings 29, the latter being disposed in a sleeve 30. This sleeve is slipped in position in extension 10^a and the lower portion of said sleeve is slotted as indicated at 31 to permit the passage of pistons 22 therethrough. The upper end of 55 each cylinder 24 is formed convex as indicated at 32 and bears against the inner periphery of sleeve 30, as shown in Figure 2, trunnions 28 being arranged concentric with 60 the axis of sleeve 30 so that the curved face of the cylinder travels over the inner face of said sleeve.

65 Cylinders 24 being freely mounted in extensions 10^a and pistons 22 having rigid con-

nections with eccentric straps 21 it will be seen that oscillatory motion will be imparted to cylinders 24 in a definite relation with the movement of said pistons as shown in Figures 3 and 4 wherein the eccentrics, the pistons, and the cylinders are shown at their extreme positions. The convex face 32 of each piston is provided with a centrally arranged elongated opening 34 disposed at right angles to the line of movement of the cylinder and forms a port through which the compressible fluid passes into and from the cylinder. This port 34 is adapted to be brought into register with an intake port 35 and discharge port 36, both of which are formed in a plate or port member 37 which is arranged in high pressure chamber 14 and extends downwardly through a suitable opening formed in sleeve 30. The lower face of this plate is formed concave as indicated at 38 and bears against the convex head of cylinder 24. This face 38 terminates flush with the inner periphery of sleeve 30 and is disposed concentrically with the axes of trunnions 28.

90 In order to insure proper positioning of member 37, a dowel pin 39 is used to align apertures formed in the overhanging portion of plate 37 and the respective side of extension 10^a. Outlet or discharge port 36 95 extends upwardly and opens into the high pressure chamber 14, while inlet port 35 is in the form of a shallow and comparatively wide groove which extends to one side of the curved face 38 and communicates with groove 40 formed in the corresponding side of the inner face of sleeve 30 so that inlet port 35 is at all times in communication with chamber 25 and chamber 25^a formed in casing 10.

105 Each plate 37 is held in position by a bolt 41 which is threaded in the cover plate 15, the latter forming the top wall of chamber 14. Bolt or screw 41 is locked in position by a nut 44 which bears on the upper face 110 of plate 15. The lower end of bolt 41 is preferably tapered and bears on plate 37 and holds the latter in position. Preferably a small bearing piece 45 is interposed between member 37 and the lower end of screw 41 and is provided with a seat for receiving the round end of screw 41.

115 Port 36 which is in the form of a narrow elongated opening is set to one side of the vertical axis of the compressor the proper distance to enable the port 34 to be brought in alignment therewith when the eccentric occupies its lefthand position as shown in Figure 3.

120 Inlet port 35 is spaced on the opposite side of the axis of the compressor the proper distance so that when the cylinder and piston occupy positions shown in Figure 4, port 34 of the cylinder is in communication with said inlet port and permits fluid to be drawn 125 130

from the casing through said coinciding ports into the cylinder. The compressed fluid is conveyed from the high compression chamber 14 by a pipe connection 46, and a pipe connection 47 returns the fluid to the casing 10 from which it is then drawn into the cylinder.

As shown in the drawings, the compressor is provided with two compression units or cylinders but, if desired, only one unit may be used, or the compressor can be formed with a plurality of compressing units.

In Figures 7 to 9 is shown the preferred form of coupling to be used in connection with my improved compressor and this coupling consists of a driving member 49 connected to the motor shaft 50 and a driven member 51 connected to the projecting end of shaft 19. These members are operatively interconnected by a rod 52 having ball and socket connections 53 and 54 with the driven and driving members, respectively. This rod 52 is provided in its length with a spherical enlargement 55 which has a bearing at 56 in a transverse wall 57 of a housing or shell 58 which is fixed to one of the plates 16. This wall 57 divides housing 58 into two compartments, compartment A which houses driven member 51 and may be completely filled with grease or other suitable lubricant, and compartment B which is provided with a central opening for accommodating the bearing of motor M and is preferably filled with oil to provide lubrication for driving member 49 which is housed in said compartment B.

Enlargement 55 is of comparatively large diameter to provide proper bearing surface for the member 52 and preferably has a bearing in a collar 59 which is seated in wall 57 and has a concave seat for receiving one-half of said ball 55. A member 60 is provided with a concave seat for receiving the other half of said ball so that the latter is held in position by members 59 and 60. While member 59 is rigidly seated in wall 57, member 60 is held in engagement with said ball 55 under pressure by means of coiled springs 61 which are spaced from said ball and have one of their ends bearing against a collar 62 carried by a bolt 63, which latter is seated in wall 57 and projects laterally therefrom through apertures formed in member 60. The other ends of springs 61 bear against said member 60 and maintain the seat thereof under pressure in engagement with ball 55, thereby forming a fluid-tight joint and preventing escape of fluid from the casing 10 to the atmosphere.

Members 59 and 60 are preferably provided with inserts of special anti-friction metal for engaging ball 55, thereby prolonging the life of the seal and reducing the friction to minimum. The ball and socket joints 53 and 54 each consists of a spherical

member 64 which is attached to the end of rod 52 and is seated in a semi-spherical seat formed in a block 65 which latter is inserted in a bore 66 formed in each member 51 and 49 for that purpose. Each ball 64 is held in position by a collar 67 screw-seated in the opening 68 of each member and having a seat for engaging said ball and holding it in position. Each collar 67 has a countersunk bore communicating with seat 69 and 75 held outwardly to accommodate rod 52.

In the assembling of the coupling, two members 49 and 51 are disposed in their ball seats 65 at diametrically opposed points and member 52 is disposed obliquely with ball 80 64 occupying said seats. Rotation of driving member 49 will rock member 54 in a circular motion with the ball 55 serving as the axis or pivot for member 52 and this circular motion will be imparted to driven member 51 causing the latter to rotate. In this manner, compartment A is effectively sealed so that all danger of leakage of the fluid from the casing to the atmosphere is reduced to minimum.

In Figure 10 is shown packing 70 preferably of lead which is placed between the flange of plate 37 and the adjoining wall of high compression chamber 14. One or both of the surfaces are formed with V-shaped 95 grooves for receiving packing 70 and when screw 41 is turned to bear on plate 37, packing 70 is forced under pressure in sealing contact with the cooperating surfaces. Furthermore, said packing forms a yielding 100 spacing means whereby by turning screw 41 in proper direction, the concave face of plate 37 can be maintained at all times in contact with the curved end of the cylinder 24. A packing 71 is placed between nut 44 and 105 cover plate 15 and a packing 72 is used to seal the joint between the walls of the compression chamber and cover plate 15.

In the modified form shown in Figure 11, a head 73 is formed detachable from cylinder 110 74, the joint therebetween being sealed by a packing 75. The curved face of the head 73 bears against the inner periphery of a sleeve 76, which is provided with an inlet port 77 and an outlet port 78 for cooperating 115 with a port 79 in the head 73. In this manner, the pressure is applied to the head 73 which contacts with sleeve 76 and it is not necessary to use bearing plate 37 and pressure member 41.

In the form shown in Figures 12 to 18, a sleeve 80 which is similar to sleeve 30 of the preferred form is provided with ports 81 adapted to establish intercommunication between ports 34 of cylinders 24 and ports 125 36^a of bearing plates 37^a. These bearing plates are seated in a horizontally disposed transverse wall 82 of casing 10^b and are provided with annular seats for receiving sleeve 80. The concave faces of plates 37^a bear 130

against the outer periphery of sleeves 80 while the convex faces of cylinders 24 operate against the inner faces of said sleeves. Sleeve 80 is rotatably journaled in bearings 83 which are mounted in end plates 16^b. Thus sleeve 80 is free to move about its axis, thereby bringing port 81 out of register with ports 36^a and 34 as shown in Figure 18 in which position the communication between ports 36^a and 34 is interrupted and the inlet port 84 formed in sleeve 80 is brought in register with the ports 34, thereby by-passing the discharge ports 34 of cylinders 24 through the intake ports 84 and connecting said cylinders with the interior of the casing so that no compression takes place in the cylinders so long as sleeve 80 occupies the position shown in Figure 18. In this manner, the motor used for driving the compressor is relieved of all the load during the starting operation thereof. When the motor reaches the proper speed, sleeve 80 is automatically operated in the opposite direction, thereby bringing ports 81 in register with ports 36^a and disconnecting the unloading connection between the cylinders and the casing.

Any suitable means may be used to position sleeve 80, the preferred form being shown in Figures 12 to 16, inclusive. In this form, a member 85 is slidably mounted on shaft 19 between eccentrics 20 and is provided with an annular groove 86 for receiving the ends 87 of bell cranks 88. The latter are pivotally mounted at 89 to a plate 90 which is arranged to one side of one of the eccentrics 20 and has fixed relation therewith. Bell cranks 88 are provided on their opposite ends with weights 91 which when shaft 19 reaches its proper speed are thrown outwardly by centrifugal action, thereby rocking bell cranks 88 which through their interengagement of ends 87 with member 85 cause the latter to move longitudinally of shaft 19 a predetermined distance.

Member 85 is provided with a truncated cone portion 92 which is adapted to engage a cone-shaped roller 92 carried by the lower end of arm 94. This arm is fixed to sleeve 80 and when roller 93 is engaged by cone face 92, the lower end of arm 94 is moved outwardly away from shaft 19, thereby rocking sleeve 80 in one direction.

A spring 95 is connected at one end to casing 10 and at its opposite end to arm 94 and tends to maintain sleeve 80 in operative position, in which position port 81 registers with port 36^a. Rods 96 project laterally from weights 91 and have secured to their ends springs 97. These springs exert their influence in a direction opposed to centrifugal action and serve to hold weights 91 in contracted positions with member 85 occupying position as shown in Figure 12. When in this position, roller

93 rests against the large end 92^b as shown in Figure 16 with sleeve 80 occupying position as shown in Figure 18 wherein port 34 communicates with intake port 84 thereby passing the compression chamber so that compression cannot take place. This relieves the motor of heavy load during the starting operation, thereby safeguarding the motor and permitting it to reach its operating speed in proper time. 75

Springs 97 are so tensioned that when the apparatus reaches the desired speed, the centrifugal force overcomes the tension of said springs and causes weights 91 to fly outwardly (Figure 13). In doing so, member 85 is moved longitudinally on shaft 19 bringing the reduced portion 92^a in contact with roller 93. This allows arm 94 to rock toward shaft 19 so that sleeve 80 is partially rotated to bring port 81 in register 85 with port 36^a. Thus the by-passing connection is interrupted and the compressor is rendered operative.

Trunnions 28 may be journaled in cone-shaped roller bearings 98 and interposed between the inner bearings is a coiled spring 99 (Figure 12) which automatically takes up the wear. 90

In the construction and operation of my improved compressor no check valves are necessary thereby eliminating all noises incidental to the operation of such valves and also rendering the compressor more reliable as all trouble caused by the inefficient operation or breakage of the valves is thereby eliminated. 95

While I have shown the preferred form of my invention, it is obvious that changes in the size, form and construction of the various parts of my device, may be made and substituted for those herein shown and described, without departing from the spirit of my invention, as expressed in the following claims. 105

I claim:

1. A compressor comprising a casing, a cylinder having a closed head provided with a port, said cylinder being mounted in said casing for oscillatory movement, a reciprocating piston operating in said cylinder and adapted to oscillate the same, and a stationary plate removably arranged in said casing and forming a bearing for said closed head of said cylinder and provided with inlet and outlet ports spaced from each other and adapted to communicate with the port of said cylinder in a definite relation with the movement of said piston. 115

2. A compressor comprising a casing, a cylinder mounted therein for oscillatory movement and provided with a closed head having a port formed therein, a reciprocating piston operating in said cylinder, and a stationary plate secured in said casing and forming a bearing for said closed head of 120 130

said cylinder and provided with an intake port and an outlet port, said cylinder being adapted to oscillate in a predetermined relation with the operation of said piston to

5 position the port of said cylinder in register with said intake or said outlet port.

3. A compressor comprising a casing having a cylinder chamber and a high pressure chamber, an oscillatory cylinder mounted 10 in said cylinder chamber, said cylinder being provided with a closed head having a convex face, there being an elongated port formed in said head transversely of the line of oscillation, a reciprocating piston operating 15 in said cylinder, and a plate mounted in said casing and separating the cylinder chamber from a high pressure chamber, said plate having a concave face for receiving the convex end of said cylinder and being 20 provided with elongated intake and outlet ports spaced from each other, said cylinder being adapted to oscillate in a predetermined relation with the operation of said piston to position the port of said cylinder alternately 25 in register with said intake port and said outlet port.

4. A compressor comprising a casing provided with a cylinder chamber and a high pressure chamber, a cylinder mounted in 30 said cylinder chamber for oscillatory movement and having a closed convex head provided with an opening, a bearing plate in said casing separating the cylinder chamber from said high pressure chamber, said plate 35 being provided with an intake port registerable with the opening in said cylinder head when the latter is rocked in one position, and with an outlet port opening into said high pressure chamber and registerable with the opening in said cylinder when the latter is 40 moved in the opposite direction, and a reciprocating piston in said cylinder, and means for actuating said piston and effecting oscillatory movement of said cylinder.

45 5. A compressor comprising a casing provided with a cylinder chamber and a high pressure chamber, a cylinder mounted in said cylinder chamber for oscillatory movement and provided with a closed head having a convex face, there being an elongated slot formed in said head disposed at right angles to the line of movement thereof, a piston operating in said cylinder, a bearing plate arranged in said casing and separating the cylinder chamber from the high pressure chamber, said plate being provided with an outlet port and an inlet port spaced from each other and disposed at right angles to the line 50 of movement of said cylinder whereby the slot formed in the head of said cylinder is brought into communication with the respective ports, thereby admitting fluid into the cylinder during the intake stroke of the piston and discharging the compressed fluid 55 through said outlet port into said high pressure

sure chamber during the compression stroke of the piston, and means for actuating said piston and producing oscillatory movement of said cylinder.

6. A compressor comprising a casing provided with a main chamber and a cylinder chamber, a shaft journaled in said main chamber, an eccentric fixed on said shaft, an eccentric strap operating over said eccentric, a piston fixed to said strap and extending into said cylinder and chamber, a cylinder in the lastmentioned chamber and engageable by said piston, trunnions laterally disposed on said cylinder and journaled in said cylinder chamber to permit oscillatory movement of said cylinder, a plate fixed in said cylinder chamber for engaging the head of said cylinder, said head being provided with a centrally disposed port leading from said cylinder, and said plate being provided with inlet and outlet ports spaced from each other and adapted to establish communication with said cylinder port when said cylinder is moved in opposite directions, and pipe connections communicating with said outlet port.

7. A compressor comprising a casing provided with a main chamber and a cylinder chamber, a cylinder mounted for rocking movement in said cylinder chamber and having the outer end closed and provided with an outwardly curved face, a piston operating in said cylinder, means in said main chamber for actuating said piston and rocking said cylinder, and a member having an inwardly curved face in engagement with the curved face of said cylinder, said member being provided with an intake port and a discharge port spaced from each other, said cylinder being provided with a port adapted to be brought alternately in register with said intake port and said discharge port to permit fluid to be drawn into said cylinder through said intake port and discharged under compression through said discharge port.

8. A compressor comprising a cylinder mounted for oscillatory movement and provided with a compression chamber, a piston operating in said chamber and automatically oscillating said cylinder, and a member in engagement with said cylinder and provided with an intake and a discharge port, said cylinder being provided with an opening leading from said compression chamber and adapted to establish communication with either one of said ports by the oscillatory movement of said cylinder in correlation with the operating movements of said piston.

9. A compressor comprising a casing provided with an inlet and an outlet port spaced from each other, a cylinder rockably mounted in said casing, a piston operating therein, the outer end of said cylinder being closed and provided with an opening adapted to be brought by the oscillatory movement of said

cylinder at predetermined intervals in communication with said inlet port during the intake stroke of said piston and with said outlet port during the compression stroke of said piston.

10. A compressor comprising a casing provided with an inlet port and an outlet port spaced from each other, a cylinder closed at its outer end and provided with a convex face, means for pivotally supporting said cylinder in said casing, a piston operating in said cylinder, eccentric means for actuating said piston and rocking said cylinder to bring the opening formed in the closed end 15 of said cylinder in register with said intake port and said outlet port in correlation with the strokes of said piston.

11. A compressor comprising a casing, a sleeve in said casing, bearings in said sleeve, a cylinder mounted in said bearings and disposed at right angles to the axis of said sleeve, the outer end of said cylinder being closed and curved outwardly concentrically with the inner face of said sleeve, an inlet 25 port and an outlet port formed in said sleeve and spaced from each other, there being an opening formed in the closed end of said cylinder adapted alternately to engage said inlet and outlet ports, a piston operating in said cylinder and adapted to impart oscillatory movement thereto, and eccentric means for actuating said piston.

12. A fluid displacement apparatus comprising a casing having a low pressure chamber and a high pressure chamber and ports leading therefrom, an oscillatory cylinder wholly mounted in the low pressure chamber of said casing and provided with a closed head having an elongated radial opening and 35 formed therein adapted to be brought, during the movement of said cylinder, into register with the respective ports, a piston operating in said cylinder for displacing the fluid between said chambers and means with- 40 in said casing for actuating said piston and imparting oscillatory movement to said cyl-

inder and effecting the register of the cylinder port with the ports of the respective chambers in time relation with the movement of said piston.

50

13. A fluid displacement apparatus comprising a casing having a plurality of fluid chambers and ports leading therefrom, an oscillatory cylinder wholly mounted in one of the chambers of said casing and having a closed head provided with an elongated radial opening adapted to be alternately brought into register with the respective ports, a fluid displacement piston operating in said cylinder for effecting passage of fluid 55 through said cylinder and between the respective chambers, a shaft journalled in said casing and extending therefrom, and means wholly disposed within said casing and actuated by said shaft for imparting reciprocatory motion to said piston, whereby the movement of said cylinder brings said elongated opening into register with the port of the respective chamber in time relation with the movement of said piston.

60

14. A fluid displacement apparatus comprising a casing having a plurality of fluid chambers, there being a port leading from each chamber and opening into a concave face of said casing, a cylinder mounted for oscillatory movement in said casing and provided with a closed convex head operating against said concave face, said head having an elongated radial opening adapted to engage alternately the ports of said fluid chambers when said cylinder is oscillated, thereby effecting communication between the respective chamber and said cylinder, a fluid displacement piston operating in said cylinder, an eccentric operatively mounted in said casing and an eccentric strap fixed to said piston and operating over said eccentric for actuating said piston and imparting oscillatory movement to said cylinder.

65

In testimony whereof I hereunto affix my 70 signature this 18th day of January, 1926.

JOHN O. CARREY.
